UNITED STATES PATENT OFFICE.

EDWIN R. TALLEY, OF CEDAR RAPIDS, IOWA.

DEVICE FOR THE PREVENTION OF THEFT OF AUTOMOBILES.

Application filed June 4, 1926. Serial No. 113,781.

This invention relates to a device for the prevention of the theft of automobile machines and it consists in the novel features hereinafter described and claimed.

5 An object of the invention is to provide an alarm device adapted to be applied to an automobile machine and which includes a casing adapted to be mounted upon the drive shaft housing and having spaced 10 gongs mounted therein. A clapper is pivotally mounted in the casing between the gongs and an end portion thereof extends into the housing of the drive shaft. The drive shaft is provided with outstanding 15 lugs adapted to engage the stem of the clapper thus causing the clapper to sound the gong when the shaft is rotated. A clapper controlling key is slidably mounted in the top of the casing and is connected with the 20 clapper and may be used for lifting or elevating the clapper so that the lower end of the stem thereof will be beyond the path of movement of the lugs upon the drive shaft. A locking means is provided for holding 25 the said key in an elevated position.

The parts and features are so arranged that when the driver of a machine leaves the same he may depress the clapper controlling key thus lowering the clapper and the clapper controlling key may be locked in a lowered position hence should an unauthorized person attempt to remove the machine the lugs upon the drive shaft will strike the 30 stem of the clapper and vibrate the same whereby the gongs are sounded.

In the accompanying drawing:

Figure 1 is a vertical sectional view of the device for the prevention of theft of automobiles.

40 Figure 2 is a top plan view of the same. Figure 3 is a detailed sectional view through the upper portion of the same.

The device for the prevention of theft of automobile machines comprises a casing 1 having a cover 2 mounted thereon and which is provided with a number of openings 3. The casing 1 is adapted to be mounted upon the shaft housing of the machine and is provided at its bottom with an opening 4 which registers with an opening 5 in the shaft housing. The drive shaft 7 is journaled in the housing in a usual manner and is provided at its side with outstanding lugs 8. A standard 9 is mounted in the casing 1 and spaced gongs 10 mounted upon rods 11 are also located within the casing. A bar

is pivotally mounted upon the standard 9 and may be moved vertically with relation to the standard. The clapper consists of a stem 12 having a slot 13 which receives 60 a stud 14 mounted upon the standard and the lower portion of the stem 12 passes through the registering opening 4 and 5.

The clapper is provided at its upper end with a head 15 which is disposed between 65 the gongs 10. A rod 16 passes through the center of the cover 2 and is provided at its lower end with a cage 17 which receives the upper portion of the stem 12 of the clapper and the head 15 thereof. The cage is provided at its side with openings 18 through 70 which the head may pass and in order to permit the head to strike the gongs and sound the same. The rod 16 is provided in the vicinity of its upper end with spaced 75 blades 18' which are slidably received in a groove 19 provided at the central portion of the cover 2. A collar 20 is mounted upon the rod and is located under the cover and may engage the cover to prevent the rod 80 from being withdrawn from the cover and the casing. The rod is provided at its upper end and at a point above the cover with a handle 21. A lock bolt 22 is housed in the intermediate portion of the cover 85 and may be moved by inserting a key (not shown) in a barrel 23 whereby the lock bolt may be interposed in the space between the blade or against the upper edge of the upper blade to hold the rod in a lowered position and whereby the upper edge of the slot 90 13 rests upon the stud 14. At this time the lower end of the stem 12 is disposed in the path of movement of the lugs 8 carried by the drive shaft.

In the event that the drive shaft should be rotated the lugs strike the lower end of the stem and swing the clapper upon the stud whereby the head 15 thereof passes through the opening 18 in the cage and 100 strikes the gongs 10. The sound passes through the openings in the cover 2 and consequently a warning is given that the automobile machine is being started or operated by an unauthorized person.

105 When the owner of the machine desires to use the same he uses his private key for turning the barrel of the lock whereby the bolt is withdrawn from between the blade of the rod and said rod is lifted whereby 110 the stem of the clapper is elevated so that its lower end is disposed beyond the path

of movement of the lugs carried by the drive shaft. Therefore as the drive shaft rotates the said lugs will clear the lower end of the stem of the clapper and the gongs will not be sounded.

When the device is locked any attempt to start the car will set the alarm going and if desired the device may be provided with an electric connection (not shown) which will 10 subject the unauthorized driver to an electric shock. Any type of lock may be employed for holding and moving the bolt which engages the blades of the rod.

From the foregoing description and in 15 conjunction with the accompanying drawing it will be seen that a device for preventing the theft of an automobile machine of simple and durable structure is provided and that the same may be conveniently used for 20 assuring the protection of the machine in the absence of the authorized owner thereof.

From the foregoing description of the construction of my improved device, it will be seen that I have provided a simple, inexpensive and efficient means for carrying out the objects of the invention and while I have particularly described the elements best adapted to perform the functions set forth, it is obvious that various changes in form, 30 proportion and in the minor details of construction may be resorted to without departing from the spirit or sacrificing any of the principles of the invention.

Having described the invention, what is 35 claimed is:

1. A device for the prevention of the theft of an automobile machine comprising a casing having openings and adapted to be mounted upon the drive shaft housing of the 40 automobile machine, lugs mounted upon the drive shaft of the automobile machine, spaced gongs located in the casing, a clapper

member pivotally mounted in the casing at a point between the gongs and having an end portion passing through the bottom thereof 45 and the side of the drive shaft housing, the lower end of the clapper normally lying in the path of movement of the lugs upon the shaft and means for lifting the clapper.

2. A device for the prevention of theft of 50 an automobile machine comprising a casing adapted to be applied to the drive shaft housing of an automobile machine, lugs mounted upon the drive shaft of the automobile machine, spaced gongs located in the 55 casing, a supporting stud located in the casing at a point between the gongs, a clapper stem having a slot which receives said stud said stem passing through the bottom of the casing and the housing, a head carried at the 60 upper end of the stem, a rod slidably mounted in the casing means for holding the rod at an adjusted position and a cage carried by the rod and which receives the 65 head of the clapper.

3. A device for the prevention of theft of 70 automobile machines comprising a casing adapted to be applied to the drive shaft housing of the machine, lugs carried by the drive shaft of the machine, spaced gongs 75 located in the casing, a stud mounted in the casing, a clapper shank having a slot which receives said stud said shank entering the drive shaft housing, a rod slidably mounted in the casing, a cage carried at the lower end 75 of the slot and receiving the upper portion of the clapper and having openings through which the upper portion of the clapper may pass, said rod being provided at its side with spaced blades and a locking bolt movably mounted in the casing and adapted to engage the edges of the blade.

In testimony whereof I affix my signature.
EDWIN R. TALLEY.
